Primary Examiner — T. Chase Nelson*Assistant Examiner* — Jonathan J Han(74) *Attorney, Agent, or Firm* — Bennet K. Langlotz; Langlotz Patent & Trademark Works, Inc.(57) **CLAIM**

The ornamental design for a scope mount ring, as shown and described.

DESCRIPTION

FIG. 1 is a rear perspective view of a scope mount ring showing my (our) new design;

FIG. 2 is a rear elevation view thereof;

FIG. 3 is a front elevation view thereof;

FIG. 4 is a top view thereof;

FIG. 5 is a bottom view thereof;

FIG. 6 is a left elevation view thereof; and,

FIG. 7 is a right elevation view thereof.

The broken lines in the drawings are used to illustrate unclaimed parts of the scope mount ring and form no part of the claimed design.

1 Claim, 2 Drawing Sheets(56)
